ENGINE STARTING MECHANISM

Romeo M. Nardone, East Orange, N. J., assignor
to Eclipse Aviation Corporation, East Orange,
N. J., a corporation of New Jersey

Application November 5, 1929, Serial No. 404,981

14 Claims. (Cl. 123—179)

This invention relates to an engine starting mechanism and more particularly to combined starting and ignition apparatus for internal combustion engines.

5 In starting internal combustion engines of the type employing magneto ignition and a distributor therefor, there has heretofore been proposed for such engines, starting apparatus having a booster magneto operatively associated therewith which is adapted to furnish ignition energy to the engine during the starting operation. Such booster magnetos are usually of the small high speed type drivably connected to the starting apparatus through speed multiplying means, and for the most part are electrically connected to the spark plugs of the engine through a rotatable distributor arm, this arm usually trailing a few degrees behind the distributor arm connected to the main magneto.

10 With the booster magneto thus electrically connected to a distributor arm which is rotatable in fixed relation to a rotatable portion of the engine, the proper timing relation between the booster magneto and the engine will always be maintained.

15 In some internal combustion engines, however, as for example marine engines of the two-cycle outboard type having one or more cylinders and wherein distributors of the usual type are not utilized, it may be highly desirable to employ therefor starting apparatus including a booster magneto for facilitating starting thereof.

20 It is accordingly one of the objects of the present invention to provide novel combined starting and ignition apparatus which is particularly adapted for use with internal combustion engines which are not provided with the usual distributors for the ignition current.

25 Another object of the invention is to provide in combination with combined starting and ignition apparatus novel means for insuring proper timing relation between the ignition device and engine during starting of the latter.

30 A further object is to provide in a starting mechanism for internal combustion engines, a booster magneto which is electrically connected to the engine only during the starting operation.

35 Another object is to provide in a starting apparatus having a booster magneto operatively associated therewith, novel means for simultaneously electrically connecting the magneto, and mechanically connecting the starter, to the engine.

40 A still further object is to provide in a combined starting and ignition apparatus, a novel

jaw clutch member movable into cranking engagement with an engine member, said members being so constructed as to be engageable in one position only.

45 Another object is to provide apparatus of the above character which is so constructed that the electrical circuit to the booster magneto will be broken at the same instant that the main magneto becomes operative to supply the ignition current whereby damage to the booster magneto is prevented.

50 The above and other objects will appear more fully hereinafter in the following detailed description when taken in connection with the accompanying drawings. It is to be expressly understood however, that the drawings are for purposes of illustration only and are not to be taken as a definition of the limits of the invention, reference being had for this purpose to the appended claims.

55 In the drawings wherein like reference characters refer to similar parts throughout the several views:

Fig. 1 is a vertical section illustrating one embodiment of the present invention;

Fig. 2 is a plan view, partly in section, taken on the irregular line 2—2 of Fig. 1;

Fig. 3 is a horizontal section taken on the irregular line 3—3 of Fig. 1;

Fig. 4 is a perspective view of one form of 60 starter jaw and engine member that may be employed in accordance with this invention; and

Fig. 5 is a view similar to Fig. 4 with the exception that the starter member has been rotated 180°.

65 Referring more particularly to Figs. 1 and 3 the starting apparatus comprises a housing constituted by a vertical cylindrical portion 5 having a circular flange 6 formed integrally therewith, and a horizontal rearwardly extending portion 7 which may be formed integrally with portion 5. The flange 6 is adapted to be secured in any suitable manner, as by means of screws 8 to a bracket 9 fixed to any convenient stationary portion of the engine to be started. Rotatably mounted within housing portion 5 is a jaw clutch member 10, normally disengaged but movable to engage and crank an engine member 11 securely attached to a rotatable portion of the engine to be started, such as for example flywheel 12.

70 Means are provided for manually rotating the starter member 10, although it is to be expressly understood that power means may be em-

20

55

ployed for this purpose if desired. In the form shown such means includes a longitudinally extending cranking shaft 13 provided with the usual cranking pin 13a and rotatably mounted in housing portion 7 as by means of ball bearings 14 and 15. Adjacent the central portion, the shaft carries a worm 16 which is adapted to mesh with a worm wheel 17. A shaft 18, rotatably mounted in housing portion 5 as by means of ball bearings 19 and 20 carries the worm wheel 17 which is drivably secured to said shaft as by means of a key 21. A nut 22 threaded on the upper end of the shaft maintains the worm wheel and ball bearings in proper operating relation with respect to the shaft.

The jaw clutch member 10 is provided with an internally splined cup portion 23 which receives the lower splined end portion of the shaft 18. This splined connection between the shaft and jaw clutch permits of relative movement of the latter with respect to the former in order that the members 10 and 11 may be engaged for starting purposes.

In order that the last mentioned engagement may be attained in a simple and efficient manner, there is provided a novel means which is preferably automatic in operation. In the form of the invention illustrated, see Figs. 1 and 4, such means is constituted by a split band 24 frictionally engaged with the outer surface of the cupped portion 23 of the starter jaw 10 and which is formed in such a manner that the ends of the band are spaced apart so as to form a diagonally extending slot 25. This slot is adapted to receive the end of a screw 26, threaded into the side wall of casing 5, the cooperation therebetween causing a combined rotary and outward movement of the starter jaw when the shaft 23 is rotated.

A booster magneto 27 is rigidly secured in any suitable manner to the casing portion 7, and means are provided for driving the magneto armature from the shaft 13 during the starting operation. To this end, the inner extremity of the shaft is provided with a bevel gear 28, Fig. 3, which meshes with a bevel gear 29 fixedly attached to the armature shaft of the magneto in any convenient manner. It is pointed out that the gear train 28-29 is a speed multiplying driving connection, thus insuring a high speed of rotation of the magneto with respect to the starter member 10 and a consequent increased number of sparks per engine revolution, in order to facilitate starting of the engine.

It will be understood that various types of speed multiplying mechanism other than that illustrated may be employed in the driving connection between the cranking shaft 13 and the magneto armature, and may be housed within the magneto casing if desired.

Novel means are provided whereby the magneto may be electrically connected to the spark plug or plugs of the engine to be started, such means preferably being automatically actuated during the starting operation. In the form shown such means include a rod 30 extending centrally through the shaft 18 and freely slideable therein, and fixedly secured at its lower end to the hub portion of starter member 10 by any suitable means such as nut 31. The upper end of rod 30 is provided with a head 32 on which there is mounted an insulating spool 33 which carries a segmental contact member 34 adapted to cooperate with contacts 35 and 36 in order to complete a high tension electrical circuit be-

tween the booster magneto and the engine during the starting operation. The two last named contacts are fixedly mounted in copper terminal members 37 and 38 carried by the insulating piece 39 which forms a housing for the contact mechanism. A cover 40 is removably mounted as by means of wing nut 41 threaded on stud 42, to permit inspection and adjustment of contact member 34. The latter adjustment may easily be effected by mounting the spool on head 32 by cooperating screw and slot connections 43 and 44, Fig. 2. The contact 36 is electrically connected to the booster magneto through the insulated cable 45 while contact 37 is connected to one or more spark plugs by means of one or more cables, one of which is shown at 46.

Novel means are provided in order to insure proper timing relation between the ignition current generated by the booster magneto and the engine to be started. In the form shown, such means is constituted by the provision of cooperating members 10 and 11, the construction thereof being such as to permit engagement therebetween in one position only. Referring to Fig. 4, the member 11 is provided with slots 47 and 48, the vertical faces of which are positioned slightly off center. Starter member 10 is provided with teeth 49 and 50 which are adapted to mesh with slots 47 and 48 respectively, said teeth being so constructed that the vertical faces thereof are also positioned off center. It is apparent from the position of the members 10 and 11 as indicated in Fig. 4, that the former may be engaged with the latter for cranking purposes. However, if the starter member 10 is rotated to any other relative position, for example 180° from the position shown in Fig. 4 to that indicated in Fig. 5, meshing of the members will be impossible since one or the other of teeth 49 and 50 will contact with the face of member 11.

It will thus be seen that whenever members 10 and 11 are engaged, the booster magneto is properly timed with respect to the pistons of the engine to be started inasmuch as the contact 34 and the armature of the magneto are in constant driving relation with respect to the starter jaw.

In employing the above described combined starting and ignition apparatus in connection with internal combustion engines of the two-cycle, outboard type, the engine jaw clutch member 11 is fixed to the flywheel 12 in any suitable manner, and the starting unit is mounted on the stationary bracket 9 so that the starter jaw 10 will be in a proper position to engage and crank the member 11.

In operation, a hand crank having a slot for engaging pin 13a is fitted over the end of shaft 13, rotation thereof imparting a rotary movement through worm 16 and worm wheel 17 to shaft 18. The starter jaw 10 because of the splined connection thereof with the shaft 18, tends to rotate therewith. The split ring 24 also tends to rotate with the starter jaw because of the frictional contact between said ring and the cup shaped portion 23, but due to the engagement between the stationary screw 26 and slot 25 such rotation is transformed into a combined rotary and longitudinal movement, thereby causing the starter jaw 10 to be moved into cranking engagement with the engine member 11. As soon as such engagement is completely effected the cooperation between screw 26 and slot 25 will prevent further movement of

the band 24 which will accordingly remain stationary while the starter jaw rotates therein.

Longitudinal movement of the starter member moves rod 30 together with spool 33 and contact segment 34 downwardly, bringing said contact into close proximity with respect to contacts 36 and 37 in order to complete the electrical circuit between the booster magneto and the spark plug or plugs of the engine to be started. It is pointed out that this electrical circuit will be completed only when members 10 and 11 are substantially fully engaged.

The construction of members 10 and 11, Fig. 4, is such that engagement therebetween may be effected in one position only, it being pointed out that the cooperating teeth and slots on the respective members are off center in order to accomplish this result. Thus when the two members are engaged, the booster magneto is properly timed with respect to the pistons of the engine to be started inasmuch as the contact 34 and the armature of the magneto are in constant driving relation with respect to the starter jaw.

The spool 33 carrying contact segment 34 is adjustable on head 32 by means of the cooperating screw and slot connections 43 and 44 and is preferably so adjusted as to complete the ignition circuit between the booster magneto and the spark plug or plugs of the engine to be started just after a dead center position of the pistons of the latter has been reached. After such electrical circuit has been completed, due to the construction of the segment 34, the booster magneto will continue to be electrically connected to the contact 35 as the starter jaw, rod 30 and spool 33 are rotated, and due to the speed multiplying connection between shaft 13 and the booster magneto the latter will deliver a plurality of sparks to the spark plug or plugs during the time the segment 34 bridges contacts 35 and 36.

Due to the speed-multiplying gearing employed between the cranking shaft 13 and the armature shaft of the booster magneto, the latter will be rotated at a relatively high speed with respect to the starter member 10, thus insuring the delivery of a plurality of sparks from the booster magneto to the engine during the starting operation.

When the engine starts the inclination of the teeth on the starter jaw is such that the latter will be quickly moved out of engagement with respect to the engine member, the extent of relative longitudinal movement between these two members being such as to instantaneously and automatically increase the air gap between segment 34 and contacts 35 and 36 whereby the booster magneto ignition circuit is interrupted. The main magneto associated with the engine is then operative to supply the necessary ignition current to the engine but since the booster magneto circuit is now open no damage can result to the latter.

There is thus provided a combined starting and ignition apparatus which is particularly adapted for use in connection with engines of the two-cycle, outboard type having one or more cylinders which fire simultaneously, and one which may be quickly and easily attached to such an engine with no change whatsoever in the ignition wiring, it being necessary only to connect additional cables to the spark plugs of the several cylinders.

The construction of the starter and engine

members insures proper timing between the engine and the booster magneto, and in addition thereto permits of instantaneous disconnection of the booster magneto from the engine as soon as the latter starts, the engine driven magneto thereafter supplying the required ignition current.

Inasmuch as the booster magneto is rotated at a relatively high speed, a small, light, compact structure may be utilized thus insuring economical and simple construction which is especially desirable in portable engines.

It is here pointed out that the rotation of the cranking shaft of the starter causes automatic meshing of the starter jaw with the engine member and simultaneously therewith, automatically establishes an electrical connection between the booster magneto and the various spark plugs.

It is further pointed out that though the invention has been described as particularly adapted for use in connection with two-cycle engines, the same may also be employed for starting four-cycle engines having one or more cylinders, it being necessary only to provide proper speed reduction means between the crankshaft and the engine member so that one complete revolution of the latter will be equivalent to one complete working cycle of the engine.

While there has been shown and described only one embodiment of the invention, it is to be expressly understood that the invention is not limited thereto, but may be embodied in various electro-mechanical forms. For example, the cranking shaft may be power operated instead of manually operated, if desired. Gear multiplying means other than that illustrated may be employed, as well as other changes in the sizes, shapes and relative location of the various elements of the apparatus, as well understood by those skilled in the art, without departing from the spirit of the invention. Reference will therefore be had to the appended claims for a definition of the limits thereof.

What is claimed is:

1. In starting apparatus of the class described, a rotatable member movable into cranking engagement with a member drivably associated with the crankshaft of an engine to be started, said members being engageable in one position only, means for rotating said rotatable member, a magneto drivably connected to said means, and means for simultaneously electrically connecting said magneto to the engine to be started and for moving said members into cranking engagement.

2. In starting apparatus of the class described, a driven member normally disengaged but movable to engage and crank a member of an engine to be started, driving means for said driven member, speed multiplying means drivably connected to said driving means, a magneto operatively connected to the driving portion only of said speed multiplying means, and means including interengaging elements for effecting a driving engagement between said members only when said members are in a position to produce proper synchronization of said magneto with the angular position of said engine member.

3. In starting apparatus of the class described, a rotatable member adapted to engage and crank a member of an engine to be started, means for rotating said member, a magneto drivably connected to said member and adapted

- to furnish ignition current to the engine during starting, means for moving said members into cranking engagement, means for causing disengagement of said members when the engine starts, and means movable by and with said engine engaging member to electrically disconnect said magneto from the engine.
4. In starting apparatus of the class described, a driven member, a driving member therefor, a magneto drivably connected to said last named member, means for moving said driven member into cranking engagement with a member of an engine to be started, and means for electrically connecting the magneto to the engine during cranking of the latter, said means including a circuit making and breaking device movable with said driven member.
5. In combination with an engine starting mechanism having a driven member movable into cranking engagement with a member of an engine to be started, means for driving said driven member, a booster magneto drivably connected to said driven member, and means movable with said driven member for electrically connecting and disconnecting said magneto from the engine.
6. In combination with an internal combustion engine of the type having an ignition device drivably connected to the crankshaft thereof, a combined starting and ignition mechanism including a starter member movable to engage and crank an engine member drivably associated with the crankshaft of the engine, a booster magneto, means for simultaneously driving said magneto and starter member, means for moving said members into cranking engagement, and means for electrically connecting said magneto to said engine in proper timed relation during starting of the latter, said means including a contact member movable with said starter member.
7. In combination, an engine starter including a rotatable member movable axially into cranking engagement with a member of an engine to be started, a magneto drivably connected to said rotatable member, and means movable in response to the axial movement of said rotatable member for electrically connecting the magneto to the engine during cranking of the latter and for electrically disconnecting the magneto when the engine starts.
8. In engine starting apparatus, a driven member, a shaft for driving said member, a magneto drivably connected to said shaft, means for moving said driven member into cranking engagement with a member of an engine to be started, means for electrically connecting said magneto to the engine during cranking of the latter said means including a contact movable with said driven member, the driven member and engine member being so constructed as to be engageable in one position only.
9. In combination with engine starting mech-
- anism including a driven member adapted to be moved into cranking engagement with a member of the engine to be started, a magneto for supplying ignition current to the engine during cranking thereof, and means to automatically electrically connect and disconnect said magneto from the engine in accordance with the engaged and disengaged positions of said members.
10. In combination with engine starting mechanism including a driven member adapted to be moved into cranking engagement with a member of the engine to be started, a booster magneto drivably connected to said driven member, means for moving said driven member into cranking engagement with said engine member, and means connected to said driven member for electrically connecting said magneto to the engine to be started.
11. In combination with engine starting mechanism including a driven member adapted to be moved into cranking engagement with a member of the engine to be started, a magneto for supplying ignition current to the engine during cranking thereof, including a contact member movable with said driven member for automatically electrically connecting the magneto and engine during cranking, and means for automatically electrically disconnecting the magneto when the engine starts.
12. In combination with a member of an internal combustion engine to be started, said engine having charge igniting means, a driven member adapted for cranking engagement with the engine member, means for rotating said driven member, ignition current supply means, and means operatively connected to said driven member for electrically connecting said supply means to the charge igniting means.
13. In starting apparatus of the class described, a rotatable member normally disengaged but movable into cranking engagement with a member of an engine to be started, means for rotating said rotatable member, a magneto drivably connected therewith, and means operable in response to movement of said rotatable member into cranking engagement with said engine member for electrically connecting said magneto to the engine.
14. In starting apparatus of the class described, a rotatable member adapted to engage and crank a member of the engine to be started, means for rotating said member, means for supplying ignition current to the engine during starting, said last named means comprising a rotatable circuit closing member and a driving connection between said rotating means and said circuit closing member, and means for moving said rotatable member into cranking engagement with said engine member only when said engine member is in a predetermined angular position with respect to the angular position of said circuit closing member.

ROMEON M. NARDONE.
